UNITED STATES PATENT OFFICE.

LEMON M. REED, OF CLEVELAND HEIGHTS, OHIO, ASSIGNOR TO HATTIE E. GYNN, OF CLEVELAND HEIGHTS, OHIO.

SPRING-SEAT.

1,359,528.

Specification of Letters Patent. Patented Nov. 23, 1920.

Application filed March 15, 1920. Serial No. 365,693.

To all whom it may concern:

Be it known that I, LEMON M. REED, a citizen of the United States, and residing at Cleveland Heights, in the county of Cuyahoga and State of Ohio, have invented a new and useful Spring-Seat, of which the following is a specification.

This invention relates to improvements in spring-seats for tractors and other farming machines, and pertains more especially to a seat of the character indicated which comprises two vertically spaced and oppositely arranged substantially horizontal plates and also springs supporting the upper plate from the lower plate and has the seat-proper mounted on the upper plate.

The primary object of this invention is to suspend the lower of said plates from a bracket of the framework of the tractor or farming machine and thereby render the seat capable of being arranged lower than if said plate were mounted directly on said bracket.

Another object is to render my improved spring-seat simple and durable in construction, light in weight and readily applicable to said bracket.

With these objects in view, and to attain any other object hereinafter appearing, this invention consists in certain features of construction, and combinations and relative arrangements of parts, hereinafter described in this specification, pointed out in the claims, and illustrated in the accompanying drawings.

In said drawings, Figure 1 is a central vertical section of a spring-seat embodying my invention. Fig. 2 is a horizontal section taken along the line 2—2, Fig. 1, looking downwardly. Fig. 3 is a vertical section taken along either line 3—3, Fig. 1. Fig. 4 is a vertical section taken along the line 4—4, Fig. 1. Fig. 5 is a vertical section taken along the line 5—5, Fig. 2, looking outwardly.

Referring to said drawings, 7 indicates the upper portion of a bracket adapted to be carried by the framework of a tractor or other vehicle or machine at the rear end, and 50 said bracket has a rearwardly projecting arm 8 from which my improved seat is shown supported. Said seat comprises two vertically spaced and directly opposite and substantially horizontal oblong metal plates 59 and 10 arranged over and under respec-

tively and spaced from and extending longitudinally of the bracket-arm 8, and the lower plate 10 is shown suspended from said arm by means comprising two pairs of substantially vertical bolts 12 which have their shanks rigidly secured to said lower plate as will hereinafter appear. Said pairs of bolts are spaced longitudinally of said arm. The bolts of each pair of bolts 12 (see Figs. 1, 2 and 3) are arranged at opposite side edges respectively of the arm 8 and have their shanks extending loosely through two substantially horizontal clamping bars 13 and 14 arranged respectively over and under said arm. Said bars extend transversely of 60 said arm and beyond the side edges of said arm. Each upper bar 13 lies on said arm, and each lower bar 14 is arranged next the under side of said arm. Each bolt 12 has its head 15 overlapping the top side of the bar 70 13 penetrated by said bolt, and a nut 16 is threaded onto the shank of said bolt at the under side of the bar 14 penetrated by said bolt, and said bars and the arm 8 are clamped together by and between said nut 80 and said head. Preferably each bolt of each pair of bolts 12 has its shank extending loosely through and below the lower plate 10, and nuts 17 and 18 are threaded onto said shank and arranged at and tightened against 85 the upper side and under side respectively of said plate so as to fix said bolt to said plate.

The seat illustrated comprises two laterally spaced rows of substantially vertically arranged helical springs 20. Said springs 90 are interposed between the plates 9 and 10. The two rows of springs 20 are shown arranged adjacent opposite longitudinal edges respectively of the bracket-arm 8, and the springs of each row of springs are spaced 95 longitudinally of said arm and of course longitudinally of the plates 9 and 10. Obviously therefore the bracket-arm 8 extends between the two rows of springs. Preferably each spring of each row of springs is 100 arranged in line laterally with a spring of the other row of springs.

By the construction hereinbefore described it will be observed that the upper plate 9 is supported from the lower plate 10 through the medium of two laterally spaced rows of springs, that said lower plate is suspended from the bracket-arm 8 at two points spaced longitudinally of said arm, and that my improved seat is arranged lower in rela- 110

tion to said arm than it would be if its lower plate 10 were mounted directly upon said arm.

To reduce the weight of the plates 9 and 10 (see Figs. 1, 2 and 5) each plate is provided at the adjacent end of each spring 20 with a hole 21 extending vertically through the plate. Each hole 21 is arranged in line endwise with the adjacent spring, and each 10 plate is provided at the inner end of said hole with an inwardly projecting annular flange 22 which is concentric in relation to and embraced by said spring and arranged to prevent displacement of the adjacent end 15 of said spring in relation to said plate. Also, each plate is cut away, as at 23, between adjacent springs 20, to reduce the weight of the plate, and for the same reason each plate (see Figs. 1, 2 and 4) is provided 20 centrally with an opening 24 extending vertically through and longitudinally of the plate.

Mounted on the upper plate 9 is the seat-proper 25 of my improved seat, and said 25 seat-proper covers the central opening 24 in said plate and (see Figs. 1 and 4) is secured to said plate through the medium of a bolt 26, a nut 27 and a clamping bar 28. The bar 28 overlaps the under side of 30 the upper plate 9 at opposite sides of the opening 24 in said plate. The bolt 26 has its head countersunk in the seat-proper 25, and the shank of said bolt extends loosely through and below the bar 28, and the nut 27 is threaded onto said shank at the under 35 side of said bar.

What I claim is—

1. In a spring-seat, two vertically spaced and oppositely arranged substantially horizontal oblong plates the upper of which is 40 adapted to carry the seat-proper, two laterally spaced rows of substantially vertically arranged helical springs, the springs of each row of springs being spaced longitudinally of the plates and supporting the upper plate from the lower plate, the rows of springs being far enough apart to permit the extension of a bracket-arm between said rows, and means for suspending the lower 50 plate from said arm.

2. In a spring-seat, two vertically spaced and oppositely arranged substantially horizontal oblong plates the upper of which is adapted to carry the seat-proper, two rows 55 of substantially vertically arranged helical springs supporting the upper plate from the lower plate, said rows of springs being spaced laterally to permit the extension of a supporting bracket-arm between said rows, 60 and means for suspending the lower plate from said arm at points spaced longitudinally of the plate.

3. In a spring-seat, the combination, with 65 two vertically spaced and oppositely arranged substantially horizontal plates, and

springs supporting the upper plate from the lower plate, the upper plate having a central opening, of a clamping bar extending across said opening and overlapping the under side of the upper plate at opposite sides of said opening, a substantially vertical bolt having its shank extending loosely through and below said bar and having a head countersunk 70 in the seat-proper, and a nut threaded onto said shank at the underside of said bar. 75

4. In a spring-seat, the combination, with a supporting bracket having a projecting arm, of two vertically spaced substantially 80 horizontal plates the upper of which is adapted to carry the seat-proper, said plates being arranged over and under respectively and spaced from and extending longitudinally of the aforesaid arm and also extending laterally beyond the side edges of said arm, and springs interposed at the sides of said arm between the plates and supporting the upper plate from the lower plate, the lower plate being suspended from said arm. 90

5. In a spring-seat, the combination, with a supporting bracket having a projecting arm, of two vertically spaced and substantially horizontal plates arranged over and under respectively and spaced from and extending longitudinally of said arm and also extending laterally beyond the side edges of said arm, and springs supporting the upper plate from the lower plate, the lower plate being suspended from said arm at points 95 100 spaced longitudinally of the arm.

6. In a spring-seat, the combination, with a supporting bracket having a projecting arm, two vertically spaced and substantially horizontal plates arranged over and under respectively and spaced from and extending longitudinally of said arm and also extending laterally beyond the side edges of said arm, and springs supporting the upper plate from the lower plate, of means at a plurality 105 of points spaced longitudinally of said arm for suspending the lower plate from said arm, the plate-suspending means at each of said points comprising the following:—a pair of clamping bars which are arranged at the top and bottom respectively of said arm, two substantially vertical bolts arranged at opposite side edges respectively of said arm and having their heads resting on the upper bar and having their shanks extending loosely through the bars and fixed to the lower plate, and nuts threaded onto said shanks at the under side of the lower bar. 110 115

7. In a spring-seat, two vertically spaced and oppositely arranged substantially horizontal plates the upper of which is adapted to carry the seat-proper, substantially vertically arranged helical spaced springs interposed between the plates and supporting 120 130

the upper plate from the lower plate, the lower plate being adapted to be supported from a supporting member, each plate being provided at the adjacent end of each spring 5 with a hole which extends vertically through the plate and is arranged in line endwise with said spring, and the plates being each provided adjacent each spring with an inwardly projecting annular flange which is

concentric in relation to and embraced by 10 said spring.

In testimony whereof, I sign the foregoing specification, in the presence of two witnesses.

LEMON M. REED.
